UNITED STATES PATENT OFFICE.

LOUIS C. NICHOLS, OF MILWAUKEE, WISCONSIN, ASSIGNOR, BY MESME ASSIGNMENTES,
TO ALLIS-CHALMERS MANUFACTURING COMPANY, A CORPORATION OF DELAWARE.

TRANSFORMER.

1,131,953.

Specification of Letters Patent.

Patented Mar. 9, 1915.

Application filed February 28, 1910. Serial No. 546,518.

To all whom it may concern:

Be it known that I, Louis C. Nichols, a citizen of the United States, residing at Milwaukee, in the county of Milwaukee and State of Wisconsin, have invented certain new and useful Improvements in Transformers, of which the following is a full, clear, and exact specification.

My invention relates to electric apparatus such as transformers, and the object of my invention is to ventilate and cool such apparatus in a simple and effective manner.

In transformers for large outputs now so commonly used in distribution of electricity by alternating currents, the temperature attained by the apparatus, due to its electric and magnetic resistance is a limiting factor, and many arrangements have been made for conveying away the heat incident to their operation. Air blast transformers, so called, and oil cooled apparatus are both in common use while in some cases auxiliary means have been provided for cooling the oil or air. It is to large transformers of the latter class that the present invention appertains.

The invention consists in surrounding electric apparatus with a plurality of members, preferably concentric, so located relatively to each other and connected in a manner to provide for the circulation of an insulating fluid therein and providing for air or ventilating passageways for cooling said insulating fluid.

This invention may be said to consist in certain novel details of construction and combination and arrangement of parts to be described in the specification and set forth in the appended claims.

In the accompanying sheet of drawings, Figure 1 is a sectional view of a transformer equipped with my invention; Fig. 2 is a top view of the same transformer with the cover removed; and, Fig. 3 is a front elevation, partly in section, of a transformer with a plurality of shells surrounding it.

Upon a base 10 is mounted a transformer inclosed in a casing having a main body portion 11, a bottom 12 and cover 13. Inside of the casing is a frame 14 on which is supported a laminated core 16 comprising two parts. High and low voltage windings 17 and 18 respectively are subdivided into a number of thin flat coils which present a large cooling surface, and the coils of said

windings are wound upon said core. The coils are separated from each other forming spaces through which a fluid may pass to maintain the coils in a cool and economical operating condition. Leads 19 and 20 of the coils are supported on terminal beams 21 which are provided with means for making electrical connections for said leads. The leads 22 are surrounded by insulating material 23 and pass through the cover 13 of the transformer casing and also through bushings 24 secured to said cover. The frame 14 is reinforced by bolts 25 which retain the lamine of the core in a fixed position, and two or more of the bolts 25 are provided with eyes through which hooks may pass to move the transformer proper from the casing without disturbing any of the other parts.

Referring to Fig. 1 of the drawings there is located exterior to the main casing and retained at a predetermined distance therefrom a shell 26. This shell comprises two metal parts 27 which are also held predetermined distances apart and are reinforced by brackets 28 to which the metal parts are secured by rivets. The main casing and shell are connected at their extreme end portions by conduits or pipes 29, in this way providing a system for a fluid circulation through the transformer, connecting pipes, and outside shell. Due to the shell 26 being retained at a predetermined distance from the main casing, a passageway is formed between the main casing and shell to permit the flow of a cooling fluid through said passageway. The insulating fluid in this particular case is oil, the level of which is indicated by the line o—o. When the oil comes in contact with the operating transformer it gradually becomes heated, rises, and the cooler oil takes its place causing a general upward flow within the inner transformer casing. Upon reaching the top of the casing the oil passes out through connecting pipes 29, down through the shell 26 and again enters the main transformer casing through the lower connecting pipes 29. While passing through the connecting pipes and the outer shell the oil is cooled by the circulating cooling medium which passes between the main casing and the outside shell. The insulating fluid may be cooled to any desirable degree by varying the force of the draft of cooling fluid if a fan or blower is 110

used. By using a construction of this kind a large radiating surface is obtained and the cooling of the insulating fluid becomes a very simple matter and it is done in a very efficient and inexpensive manner. Any number of these shells, having their communicating openings preferably spaced the same distance from the ends, may be employed and connected in a similar manner as indicated in the drawings of this application. In this particular case I have shown one shell exterior to the main body portion in Fig. 1 and two shells exterior to the main body portion in Fig. 3.

It is evident that there may be many modifications of the precise arrangement herein shown and described, and I aim in my claims to cover all modifications which do not involve a departure from the spirit and scope of my invention.

What I claim as new is:

1. In combination, a fluid-containing casing for electrical apparatus, and a hollow shell surrounding said casing and arranged laterally outside of all fluid-containing portions thereof, said shell being connected with and supported by said casing through the side walls of both said casing and said shell.

2. A transformer casing adapted to contain insulating fluid, a cooling shell surrounding the normal fluid-containing portion of said casing and spaced therefrom to form a ventilating passageway between said casing and said shell, and conduits connecting said casing and said shell, said conduits being located wholly within the ends of both said casing and said shell.

3. A casing for the reception of electrical apparatus adapted to contain insulating fluid, a cooling shell surrounding the normal fluid-containing portion of said casing and spaced therefrom to form a ventilating passageway between said casing and said shell, and conduit connections between said casing and said shell, said connections being located within the ends of said casing and said shell, and the outer surface of said shell permitting contact at any instant with a support having a plane surface throughout the greater portion of the axial length of said shell.

4. In combination with a casing for electrical apparatus adapted to contain insulating fluid, a hollow shell surrounding said casing and spaced therefrom to form a ventilating passageway between said casing and said shell, and tubular connecting means between said casing and said shell adjacent the upper and lower ends of said shell, said connecting means being disposed wholly within the end portions of said shell, and that portion of the connecting means adjacent the lower end of said shell communicating with the side wall of said shell at a

point appreciably removed from the lower end of the shell to form a pocket in said shell below the opening therein.

5. In combination with a casing for electrical apparatus adapted to contain insulating fluid, a hollow shell surrounding said casing and spaced therefrom to form a ventilating passageway between said casing and said shell, and means for connecting said shell to said casing, said means being located wholly within the end portions of said shell and the normal fluid-containing portion of said casing, and the axes of those portions of said connecting means immediately associated with said casing and said shell being in alinement and normal to the wall of said casing and the inner wall of said shell.

6. In combination with a casing for electrical apparatus adapted to contain insulating fluid, a hollow shell surrounding said casing and spaced therefrom to form a ventilating passageway between said casing and said shell, and tubular connections between said casing and said shell, the axes of said tubular connections being normal to the wall of said casing and the inner wall of said shell, and said connections forming a combined support for said shell and a means of communication between said casing and said shell.

7. In combination, a cylindrical casing for electrical apparatus, a cylindrical shell surrounding and spaced from said casing to form a ventilating passageway of substantially uniform width between said casing and said shell, the normal fluid-containing portion of said casing being of substantially uniform diameter, and a plurality of tubular elements associated with the walls of said casing and said shell to form a means of support for said shell and a means of communication between said casing and said shell, the axes of said tubular elements being substantially along radii of said casing and said shell.

8. A casing for electrical apparatus adapted to contain insulating fluid in which said apparatus may be immersed, a plurality of shells surrounding said casing and spaced apart radially and also spaced from said casing, means associated with the wall of said casing and the inner wall of the inner shell for supporting said inner shell, and means associated with the outer wall of said inner shell and the inner wall of the outer shell for supporting said outer shell.

9. A casing for electrical apparatus adapted to contain insulating fluid in which said apparatus may be immersed, a plurality of shells surrounding said casing and spaced apart radially and also spaced from said casing, tubular means associated with the wall of said casing and the inner wall of the inner shell for supporting said inner

shell, and tubular means associated with the outer wall of said inner shell and the inner wall of the outer shell for supporting said outer shell, said supporting means between 5 said casing and said inner shell and between said inner and said outer shells being in alinement and having their axes normal to the surface of the parts of said casing and shells with which said means are associated.

10. A casing for electrical apparatus adapted to contain insulating fluid, a plurality of hollow shells surrounding said casing, said shells being spaced apart radially 15 and also spaced from said casing, tubular connecting means between the inner wall of the inner shell and the wall of said casing adjacent its upper and lower ends, and tubular connecting means between the outer wall 20 of said inner shell and the inner wall of the outer shell whereby circulation of said fluid through said casing and said shells is provided, all of said tubular connections being located wholly within the ends of said casing 25 and said shells.

11. A casing for electrical apparatus adapted to contain insulating fluid, a plurality of hollow shells surrounding said casing, said shells being spaced apart radially 30 and also spaced from said casing, tubular connecting means between said casing and the radially inner shell, said connecting means communicating with said casing and the inner shell through their side 35 walls at points adjacent the upper and lower ends thereof, and tubular connecting

means between said shells located wholly within the ends thereof, both of said tubular connecting means forming a means for supporting said shells in position relatively 40 to each other and to said casing.

12. A casing for electrical apparatus adapted to contain insulating fluid, a plurality of hollow shells surrounding said casing, said shells being spaced apart radially 45 and also spaced from said casing, and tubular connecting and supporting means between the adjacent walls of said casing and the radially inner shell and between the adjacent walls of said shells, the axes of said 50 connecting and supporting means being normal to the walls of said casing and said shells, and a passage provided by said first means between said casing and said radially inner shell being substantially in alinement 55 with a passage provided by said second means between said inner and outer shells.

13. In combination, a casing for electrical apparatus adapted to contain insulating fluid, a hollow shell surrounding said casing and spaced therefrom, means associated with said shell and casing for supporting said shell in position, said means being disposed wholly within the ends of said casing.

Milwaukee, Wis., Feb. 23, 1910.

In testimony whereof I affix my signature, in the presence of two witnesses.
